PNEUMATIC RELOOPING MACHINE

Bedri Hussein Gostkowski, Geneva, Switzerland

Application August 31, 1937, Serial No. 161,785
In Germany September 2, 1936

8 Claims. (Cl. 66—1.5)

This invention relates to a pneumatic relooping machine.

Different machines of this kind are already known. They all consist of a pump worked by an electric motor, the air pumped by said pump acting on a piston to which is fixed the relooping needle which, consequently, effects a to and fro movement the rhythm of which is determined by the rhythm of the air pump.

10 It is also known, on the other hand, that in relooping operations, it is preferable that the needle in its rest position should occupy its rear-most position, i. e. its rear dead centre, so that on beginning the work, the first movement it executes shall always be a forward movement from the rear in the direction of the fabric to be repaired.

In the existing pneumatic machines, said result is obtained by providing the needle holder with an internal spring intended to push back the needle to its rear dead centre whenever the pump is out of action, the working then consisting in compressing air against the action of said spring, so that only one of the two movements of the 25 needle is effected pneumatically, the other being effected mechanically by the action of a return spring.

The drawback of all machines constructed on this principle is the irregular movement of the 30 needle, for said needle is subjected in one direction to an effort resulting from a cause different to that working it in the other direction. It is besides impossible to regulate the value of the effort furnished by the needle, for even if the 35 quantity of pumped air were diminished, and this would correspond to a shorter stroke or to a smaller effort of the needle in one of its working directions, said needle however would still be subjected to a variable effort, that of the 40 spring, in its other working direction.

The object of the machine according to the invention is to do away with the aforesaid drawbacks, said machine permitting of utilizing a needle holder without return spring, while having a rest position of the needle at the rear dead 45 centre and further the possibility of regulating the effort that the needle is capable of furnishing while working.

For this purpose, the machine according to the 50 invention comprises chiefly means permitting of exerting a sucking action on the piston working the relooping needle, whenever the needle ceases to work. This action generally comes from an auxiliary pump specially intended for said purpose, but can likewise come from the main pump

intended to work the relooping needle, other details and improvements will be dealt with more in detail in the following description.

Figs. 1 to 5 show a first embodiment of the invention given by way of example.

Fig. 6 illustrates a modification or second embodiment of the invention.

Figs. 7, 8 and 9 are fragmentary views of details, Figs. 7 and 9 being also partly in section, and all three figures being inverted with respect to Fig. 6.

Fig. 10 is a detail of regulation means of the apparatus of Fig. 6, while

Fig. 11 is a modification of such means.

Fig. 12 illustrates a needle holder for the invention, shown partly in section.

Throughout the views the same reference numerals indicate like parts.

Fig. 1 is a plan view of the whole machine and Fig. 2 a detail of the main pump of same; 20 Figs. 3 and 4 show in two different positions an air slide valve working electro-magnetically; Fig. 5 is a diagram of the electric connections of the whole machine.

In the plan view of Fig. 1, the electric motor 25 working the machine is designated by 1 and comprises a small pump 2 integral with same and the purpose of which is to produce the vacuum necessary for keeping the relooping needle in its rest position at the rear dead centre. By means of 30 the belt 3, the motor 1 works one of the parts 4 of a clutch 4, 5, the second part 5 of which is connected with a disk 6 bearing the crank to which is fastened the piston rod 7 of the main pump 8. At 9 is located an electro-magnet intended to work the clutch 4, 5 by means of a 35 lever 10 and of a fork 11 both moved by the movements of the core 12 of said electro-magnet. The position shown corresponds to the electro-magnet when disengaged and to the clutch when 40 unclutched; while acting on the clutch, the core 12 acts on the air distribution inside a sleeve 13 comprising for this purpose different ducts to which reference will be made hereinunder. The 45 spring 14 serves to bring back the core 12 to the position drawn whenever the electro-magnet ceases to be energized.

The impulses produced by the movement of the piston of the pump 8 are sent through the pipes 15 and the ducts of the sleeve 13 to the flexible 50 tube 16 connected with a needle holder of the type to be described hereinunder.

Fig. 2 shows in detail a device proper to the disk 6 and permitting of varying the amplitude of the movement given to the piston 17 of the 55

main pump 8. Said device consists of a pivot 18 integral with the disk 6 and of a cranked lever 19 capable of rotating about said pivot. To one of the arms of said lever, at 20 is fixed the piston rod 7. The position shown in dot and dash line shows how the displacement of the lever 19 permits of displacing the pivotal point 20 by drawing it away from or drawing it near to the centre of the disk 6, and this permits of increasing or 10 of diminishing the amplitude of the movements transmitted to the piston 17.

Said piston is finally subjected to the action of a spring 21 intended to bring same back to its rear dead centre whenever the clutch 4, 5 is unclutched. The auxiliary suction pump 2 is likewise connected with the sleeve 13 by means of the pipe 22. Figs. 3 and 4 show how said pipe 22 and the pipe 15 issuing from the main pump 8 can be connected, either with the outside air, 20 or with the outlet 23 leading to the needle holder.

Fig. 3 shows the electro-magnet 9 disengaged. In this case the outlet 23 is connected through the duct 24 and the pipe 22 with the auxiliary suction pump 2, while the pipe 15 connects the main pump by means of the groove 25 with the outside air.

Fig. 4 shows the same members, when the electro-magnet 9 is energized, in this case the internal duct 24, connects the outlet 23 with the main pump 8 through the pipe 15, while the auxiliary suction pump is connected through the groove 26 and pipe 22 with the outside air.

The electric diagram of Fig. 5 will easily permit of realising how the machine just described 35 works. The terminals 27 permit of connecting said machine with the electric network, by means of a switch 28 to be seen in Fig. 1. The machine is further completed by a foot controlled switch shown diagrammatically in the right hand portion of Fig. 5. Said switch comprises a regulable resistance 29 and a contact piece 30 and can be connected with the machine described by means of the three terminals 31. The resistance 29 and the contact 30 are placed 40 opposite each other and by means of the foot, a slideable contact so constructed as to be always connected with the resistance 29 can be made to slide between said resistance and said contact 30, whereas said movable contact moves away 45 from the contact 30, when the whole resistance is inserted, a position corresponding to what is shown in Fig. 5 and to the rest position of the reloping machine.

It will be seen that in this position of the contact of the pedal, the motor 1 runs slowly for 55 the whole resistance 29 is inserted and the electro-magnet 9 does not receive any current. The auxiliary suction pump 2 is thus working, the clutch 4, 5 is unclutched and the position of the core 12 corresponding to Fig. 3 causes the sucking action of the pump 2 to be transmitted to the needle holder.

As soon as the pedal is worked and the slideable contact moved, said contact moves along the resistance 29 the value of which diminishes and immediately reaches the contact 30, and this causes the energization of the electro-magnet 9. The core 12 is drawn at the same time as the clutch 4, 5 is clutched and sets the main pump 8 into action. As the displacement of the core 12 effects the communication between the needle holder and the main pump 8, it will be seen that the latter immediately starts the needle working. It will likewise be seen that the first movement effected by the piston 17 of the pump 8 is

a compression movement against the action of the spring 21, and this is necessary as the piston of the needle holder is in its rear dead centre position and it must in the first place be pushed forward.

By varying the position of the lever 19, a more or less hard action will be obtained on the piston of the needle holder.

In the second embodiment of the machine according to Figs. 6 to 9, the driving mechanism 10 is simplified in that the clutch is abolished. It will be seen hereinunder by what means this has been made possible.

In the plan view according to Fig. 6, the electric motor 1 is found again driving, by means of the belt 3, a shaft bearing a disk 6, to which is fastened the piston rod 7 of the main pump 8. The machine likewise comprises an electro-magnet 9, the core 12 of which is in this case used only to modify the distribution of air in 20 the sleeve 13, a spring 14 being likewise provided to keep the core 12 in the rest position shown. The auxiliary suction pump 2 is worked from the shaft bearing the disk 6 and by means of an eccentric 32. Said pump is of the oscillating 25 cylinder type, the axis of oscillation being constituted by the screw 33.

In the working position, the pulsations communicated to the air by the pump 8 are transmitted through the pipe 15 and through the slide valve to be found at 13 to the flexible tube 16, at the free end of which is situated the needle holder 34. The auxiliary suction pump 2 is likewise connected with the sleeve 13 by the pipe 22. Finally the electric diagram is similar to 35 that of the first embodiment and comprises in addition to the foot controlled contact not shown in the drawings the terminals 27, the switch 28 and the terminals 31. At 35 is located a cylindrical sleeve in which the needle holder 34 is 40 placed, when the machine is no longer being used.

The air distribution in the sleeve 13 is similar to what has been previously explained with regard to Figs. 3 and 4, i. e. in the rest position shown, the needle holder is connected by the 45 pipe 22 with the auxiliary suction pump 2, while in the working position when the electro-magnet 9 is energized, the needle holder 34 is connected by the pipe 15 with the cylinder of the main pump 8.

The piston of the needle holder 34, the rod 36 of which bearing the needle 37 can be seen in the plan view, is thus constantly kept in its rearmost position by the effect of the suction produced by the auxiliary suction pump 2. But 55 as soon as the machine starts working, said piston executes a to and fro movement pneumatically communicated from the main pump 8. It is to be remarked that said pump is always working, as there is no clutching member permitting of clutching and unclutching it.

In these conditions, said pump comprises a special device permitting it of being worked correctly and without which the machine could not be used in the case for example in which the 65 electro-magnet 9 were to be energized at the moment when the piston of the pump 8 effects its suction stroke. In this case, indeed, a vacuum would be produced in the cylinder of the needle holder 34, in the tube 16, in the pipe 15 70 and in the cylinder of the pump 8 and at the next compression stroke of the piston of said pump, the space just mentioned would not contain enough air for a positive impulse of the piston of the needle holder.

The construction of the device permitting the pump 8 of effecting its work, whatever may be the position occupied by its piston at the moment when the electro-magnet 9 is energized, is as follows. Said device is shown in Figs. 7 to 9 in which the pump 8 is again found with its piston 38 to which the piston rod 7 is articulated at 39.

Said piston rod comprises a disk 40 which is a little removed from the articulation 39, a disk which joins both in the axial to and fro movement and in the transversal oscillating movement of the rod 7. Against said disk is applied another disk 41, substantially the same in size and capable of coinciding with the first disk whenever the piston rod 7 lies in the axis of the pump, i. e. whenever the piston 38 occupies one of its two dead centres either rear or fore. In said position when said two disks coincide, bores 42, 43 bored in their centres coincide with each other, thus giving passage to the air led in a flexible tube 44 through the piston 38 into the cylinder of the pump 8 or on the contrary from said cylinder through the piston to the outside.

As shown in the position in Fig. 8, the bores 42, 43 cease coinciding as soon as the rod 7 moves laterally.

The disk 41 indeed only joins in the axial to and fro movement of the piston 38, but not in the lateral oscillating movement, as it is secured to the piston 38 by means of two elastic blades 45 intended to apply the disk 41 firmly against the disk 40.

In the case already mentioned in which the electro-magnet were to be energized when the piston 38 effects its sucking stroke, it will be seen that at the end of the stroke, at the moment when the rear dead centre is being passed over, when the bores 42, 43 coincide, the cylinder of the pump 8, the pipe 15, and the tube 16 can be instantly filled with air thus permitting the piston 38 of transmitting its impulse to the piston of the needle holder 34.

There is no need to deal with the starting position of the piston 38 when the work is begun. Similarly, any eventual losses or leakages in the pipes transmitting the air pulsations are without importance for at the end of each compression stroke the cylinder of the pump 8 is entirely emptied and at the end of each sucking stroke it is possible for same to be filled completely.

This very important fact permits of providing the machine according to the invention with means regulating the effort transmitted to the needle, consisting simply in an air escape that can be regulated, and which is introduced in the circuit travelled over by said air.

Fig. 10 shows such regulating means. Said figure shows the main pump 8 with its piston 38 and the pipe 15 issuing from said pump. On said pipe is inserted a cock 46 closed by a conical obturator and permitting the air of escaping outside through an outlet 47. The amount of air escaping can be regulated by turning the lever 48. It is obvious that if the amount of air escaping is very great, the greater part of the work furnished by the pump 8 will be lost and only a small part will be transmitted to the needle holder, while if the escape is suppressed, all the work of the pump will be transmitted. It is thus possible in this way to regulate continually, while the machine is running, the action 75 of the relooping needle which, according to the

force of the impulses received, will furnish more effort with a greater amplitude or less effort with a smaller amplitude.

Fig. 11 shows another way of obtaining a regulation like the one just described. According to this example, a cushion of air 49 of variable volume is introduced in the pipe 15. The modification in volume is obtained by means of a piston 50, which can be moved by means of a lever 51 and a cam 52 against the action of a 10 spring 53. It is obvious that if said cushion of air is relatively great in volume, it will absorb part of the work furnished by the pump 8, while if its volume is small or even if it could be reduced to zero, all the work of the pump 8 would be transmitted entirely to the needle holder. Said cushion of air 49 thus acts like an elastic member of variable tension introduced between the propulsive members and the members worked by the machine.

The machine just described could be further simplified in that the auxiliary suction pump 2 could be suppressed by using the main pump 8 in order to produce the sucking action required to keep the relooping needle 8 at its rear dead centre when said needle is at rest.

Fig. 12 shows finally how the needle holder referred to in the description of the different embodiments given by way of example works. Said needle holder consists of a cylinder 34, in which a piston 58 bearing the rod 36 and the needle 37 can move. Normally, it would be sufficient to dispose at either end of the stroke of the piston 58 a very small spring just sufficient to deaden the blows of the piston against both ends of the cylinder. According to the invention, springs 59 and 60 are provided which are longer than would be necessary to deaden the blows, their length in the axial direction being about a third of the total free length in the cylinder 34. The reason for this arrangement is the following.

When the proportion of the effort transmitted by the pump 8 to the needle holder is regulated, for example by acting on the cock 46 in Fig. 10 or by modifying the size of the cushion of air in Fig. 11, the value of the force transmitted to the piston 58 is modified. Now, if said force is very small, the piston oscillates in the free space between the two springs 59 and 60, without, so to say, compressing said springs. The amplitude of the movements of the needle 37 is thus relatively small, but in proportion as the force transmitted to the piston 58 increases, the latter compresses the springs 59 and 60 more and more and the amplitude of the movement obtained increases. Thus, it is possible to act on the amplitude of the movements of the relooping needle to a fairly large extent, and this would not be possible with small ordinary deadening springs.

It is obvious that the means described to obtain the results sought after and in particular to make it possible for the main pump 8 to be filled and to be emptied completely at each sucking or compression stroke, may differ from what has been described without departing from the scope of the invention.

What I claim is:

1. A pneumatic relooping machine comprising a cylinder member serving as a needle holder containing a reciprocable piston to which a relooping needle is attached, a motor driven air pump having a pump cylinder containing a pump piston and being connected to said cylinder member so that the air from the pump will act upon said

- piston and cause the same and said needle to reciprocate in rhythm with said pump, driven suction means, and means bringing said cylinder member into active communication with said suction means when the piston is at rest in order to retain said piston in retracted rest position.
2. A pneumatic relooping machine comprising a cylinder member serving as a needle holder containing a reciprocable piston to which a relooping needle is attached, a motor driven air pump having a pump cylinder containing a pump piston and being connected to said cylinder member so that the air from the pump will act upon said piston and cause the same and said needle to reciprocate in rhythm with said pump, a motor driven auxiliary pump comprising an elastic member capable of producing a suction effect in order to return the needle to rear dead center when the pump is at rest, a connection between the air pump and cylinder member and an air slide valve controlling said connection, a clutch between the motor and the air pump, and an electromagnet capable of operating said slide valve and said clutch so that when said motor is stopped the electromagnet unclutches the motor from said air pump and establishes a connection between said cylinder member and said auxiliary pump, and when the motor is running said electromagnet clutches the motor with the air pump and causes the slide valve to pass air through said first connection to said cylinder member so as to operate the needle.
3. A machine according to claim 2, wherein the electromagnet is provided with a movable core, said air duct being capable of connecting the air pump with the cylinder member in one position of said core when said electromagnet is energized and of connecting said cylinder member with the auxiliary pump in another position of said core in de-energized condition of said electromagnet.
4. A machine according to claim 2, wherein the main air pump is provided with means capable of opening communication between the interior of

the pump cylinder and the atmosphere upon approach of the pump piston to either end of its stroke.

5. A machine according to claim 2, wherein the pump piston of the main air pump has a piston rod provided with a disk which partakes of all the movements of said piston rod and a second disk is applied against the first disk and partakes of the movements of the pump piston, and wherein both disks have central bores which coincide upon approach of said piston to either end of its stroke, and the central bore of the first disk communicates with the interior of the pump cylinder.

6. A machine according to claim 2, wherein the motor is connected to an invariable current supply and a resistance means is included in the connections from said current supply to the motor, allowing said motor to operate at a sufficient speed to maintain the auxiliary pump operating effectively to retain the relooping needle and the piston to which it is attached in retracted rest position, and wherein a contact in said connections is movable along said resistance means and capable upon reduction of the acting resistance by movement along the resistance means to close the circuit of the electromagnet and cause the same to operate and effect communication between the cylinder member and the main air pump.

7. A machine according to claim 1, wherein the connection between the air pump and the cylinder member of the relooping needle comprises a connecting member having adjustable outlet means capable of bringing said connecting member into communication with the atmospheric to a degree which is variable at will.

8. A machine according to claim 1, wherein the cylinder member is interiorly provided with a spring at each end occupying about one third of the length of the interior, the piston to which the relooping needle is attached moving between the two springs and both springs being substantially equal in resistance.

BEDRI HUSSEIN GOSTKOWSKI.
